UNITED STATES PATENT OFFICE.

DE WITT C. RUFF, 2D, OF ST. PAUL, AND JAMES H. HEALY, OF MATHOMEDI, MINNESOTA, ASSIGNORS TO JOHN A. HEALY, JAMES H. HEALY; AND DANIEL W. HICKEY, ALL OF ST. PAUL, MINNESOTA.

RADIATOR HANGER.

Application filed February 21, 1924, Serial No. 694,249. Renewed November 18, 1925.

This invention relates to improvements in radiator hangers, and particularly to heads for such hangers, adapted to be secured to a wall for supporting a radiator thereon.

5 It is our object to produce such hangers at a reduced cost and at the same time to facilitate the work of hanging radiators by providing a support which permits unusually easy and quick adjustments and fastenings for radiators of differing shapes and sizes.

A further object of our invention is to provide a head for a radiator hanger adapted to be mounted either directly upon a wall 15 or to be spaced a predetermined distance away from the wall.

Another object is to provide a simple attachment adapted to be quickly and easily secured to the head proper to off-set it from 20 a wall. The radiator hangers in common use are made of cast iron, while our device is designed to be made of strap metal with resultant lightness, strength and compactness in packing and shipping. Our invention 25 also includes certain novel features of construction which will be hereinafter more fully pointed out and claimed.

Referring to the drawings which illustrate the best form of our device at present known 30 to us; Figure 1 is a detail perspective view of our improved head for a radiator hanger, Fig. 2 is a side elevation of the hanger mounted on a wall, the off-set being shown in central, vertical section, and the position 35 of the radiator being indicated in dotted lines; Fig. 3 is a plan view of the head separate from the off-set; Fig. 4 is a front elevation of the head; Fig. 5 is a plan view of the head off-set; Fig. 6 is a front elevation of 40 the same; and Fig. 7 is a plan view of the bare off-set.

Our improved hanger head is preferably made of sheet metal, and has a normally vertical back 10 formed with a base flange 11 and a top flange 12 against which the coils 45 of a radiator 13 are held. The back 10 of the head has a square aperture 14 adapted to receive the nut on an anchor bolt 15, and a slot 16 extending upward from the aperture 14 is arranged to engage the anchor bolt behind its nut. Vertical slots 17, formed in the 50 back 10 on opposite sides of the aperture 14, are arranged to receive flanges 18 on the forward edge of an off-set 19. Enlarged

lower portions 20 of the slots 17 permit insertion of the flanges 18, which after being inserted therethrough, are free to pass into the narrow portions of the slots 17 where said flanges securely engage the back 10 of the hanger head. The off-set 19 is substantially rectangular, having forwardly projecting flanges 21, disposed to bear upon the head, and a panel 22 adapted to be placed against the wall. This panel 22 of the off-set is formed with an aperture 23 and vertical slot, like the aperture 14 and slot 16 in the head proper, arranged to receive the anchor bolt 15. To prevent the head from tilting on the wall, a triangular tooth 24 is formed on the off-set 19, and a similar tooth 25 is formed on the back 10 of the head proper.

The base flange 11 is formed with a slot 26 through which the normally vertical rod 27 of the hanger projects. A nut 28 on the upper end of the rod 27 is held against rotation thereon by an up-turned edge 29 on the flange 11. The rod 27, which is suspended from the nut 28 on the hanger head, carries a bracket 30 on its lower end which supports the radiator 13. The rod 27 is maintained in proper vertical position by an off-set 31 adapted to engage the wall 32 above the base board 33.

To hold the radiator 13 against the flanges 11 and 12, a bolt 34 is secured at one end in the hanger head as hereinafter described and is provided at its other end with a disc 35 adapted to be inserted between the radiator coils, and to engage them after insertion. A nut 36 threaded on the bolt 34 is adapted to be held in any pair of a series of fingers 37 formed on the front of the flange 12. These fingers 37 extend upward from the flange 12 and then back toward the wall so as to engage the nut 36 to prevent it from coming out at the top or turning. The fingers 37 are formed by slots 38 just wide enough to receive the shank of the bolt 34.

Obviously, at least a pair of our radiator hangers must be used to mount a radiator on a wall, but the operation of our device will be clear from the following description referring to a single hanger. The head proper of our device can be used either with or without the off-set 19. Where it is desirable or necessary to mount a radiator close to the wall, the off-sets 19 and 31 are not used, the back 10 of the head being placed

upon the wall. To mount a radiator close to the wall, the anchor bolt 15 being already embedded, the hanger head is placed upon said bolt by inserting the nut on said bolt 5 through the aperture 14 and then sliding the hanger down until the bolt engages the back 10 at the margins of the slot 16. When this is done, the tooth 25 is driven into the wall beneath the anchor bolt to prevent tilting. 10 The rod 27 carrying the bracket 30 is now inserted in the slot 26 and suspended from the nut 28. The radiator is now placed on the bracket 30, and after inserting the bolt 34 and retaining disc 35 between the coils, 15 the threaded end of said bolt is dropped into one of the slots 38 with the nut 36 into place. The nut 36 is held against turning by the fingers 37 and the upper end of the radiator may be drawn snugly against the hanger 20 head by turning the bolt 34 in the nut 36. For convenience in turning the bolt 34, its head is formed with a kerf adapted to be engaged by a screw driver inserted between the radiator coils. 25 To space the radiator a greater distance from the wall, as is frequently necessary, the off-sets 19 and 31 are employed. To secure the off-set 19 to the head, before the head is secured to the anchor bolt 15, the lugs 18 30 are inserted through the slots 20, when the head is moved down on the off-set until said lugs engage the margins of the slots 17. The off-set carrying the head is now hung upon the anchor bolt 15, the nut on the 35 anchor bolt being inserted through the aperture 23 and the tooth 24 being embedded in the wall to prevent tilting. The off-set 31 is then placed on the rod 27 by inserting said rod through the sleeve 31^a. The radiator is finally suspended from the flange 40 11 and secured at its upper end as described above. As will be readily understood, the weight of the radiator and hanger maintains the lugs 18 within the restricted upper 45 ends of the slots 17.

Our hanger has the advantage of making it unnecessary to exactly place the anchor bolt 15 in a predetermined position on the wall. The height of the bracket 13 can be 50 adjusted by turning the nut 28 the proper distance on the rod 27 and lateral adjustment is permitted by the horizontal slot 26, through which the rod 27 passes, and by the several slots 38 into any one of which the bolt 34 may be dropped. It is unnecessary 55 after the radiator is in place to manipulate the nuts on the bolts 15 or 34 or on the rod 27. Further, the bracket presents an unusually neat appearance by reason of the 60 concealment of the anchor bolt and nut and bracket supporting nut 28 beneath the flanges 21 and 12. By providing a single head proper adapted either to be mounted directly on the wall or to be off-set there- 65 from, the cost of the hanger is reduced.

Thus, where heretofore two distinctly different types of hangers have been necessary, our invention supplies the need for both types.

Having described our invention what we claim as new and desire to protect by Letters Patent is:

1. A radiator hanger comprising, a head formed with a back adapted to be hung upon a wall, a forwardly projecting flange on said head, a bracket for a radiator arranged to be suspended from said flange, and an off-set adapted to be removably attached to the back of said head and arranged when so attached to support said head upon a wall at a predetermined distance therefrom. 80

2. A radiator hanger comprising, a head formed with a flat back adapted to be hung upon a wall, a forwardly projecting flange on said head, a bracket for a radiator arranged to be suspended from said flange, and an off-set adapted to be removably attached to the back of said head and formed with an aperture disposed to receive an anchor bolt for securing the same to the wall, whereby said head may be supported upon a wall at a predetermined distance therefrom. 90

3. A radiator hanger comprising, a head formed with a flat back adapted to be hung upon a wall, a forwardly projecting flange on said head, a bracket for a radiator arranged to be suspended from said flange, and a rectangular off-set formed with a normally vertical panel, top and side flanges disposed to bear upon the back of said head, and lugs 100 formed on said side flanges to detachably engage said head and means for selectively securing said vertical panel and the back of said head to a wall. 100

4. A radiator hanger comprising a back 105 panel and forwardly projecting top and bottom flanges, an upwardly bent portion on said top flange, a bracket adapted to support a radiator suspended from said bottom flange, said top flange having a multiplicity 110 of slots extending downward from the upper edge of said upturned portion and said slots forming a plurality of pairs of fingers, adapted to selectively receive a bolt between them and means for maintaining a radiator 115 in upright position on said bracket, consisting of a normally horizontal bolt having means for engaging the radiator coils on one end, the other end of said bolt being adapted to be selectively inserted in any of said slots 120 and a nut on said last mentioned end of said bolt, adapted to be removably held by said fingers, whereby the position of said bolt may be adjusted relative to said head to register with an opening between vertical members of a radiator. 125

5. In a radiator hanger, a supporting member, means to space the radiator from a wall carried by said supporting member, a substantially vertical member carried by 130

- 5 said supporting member and adapted to abut against the radiator, said substantially vertical member being formed with a multiplicity of slots extending from the free edge thereof and forming pairs of fingers adapted to selectively receive a bolt between them, means for supporting the weight of the radiator from said spacing means only, and means for maintaining a radiator in upright position on said support comprising a substantially horizontal bolt provided with a member adapted to engage the coils of a radiator upon its outer end, the inner end of said bolt being adapted to be selectively inserted in any of said slots, and means on the inner end of said bolt adapted to engage said fingers, said slots being arranged to receive said bolt with said finger engaging means in place thereon, whereby the position of 15 said bolt may be adjusted relative to said head to register with an opening between vertical members of a radiator.
6. A radiator hanger comprising a head formed with the back adapted to be hung upon a wall, means for suspending a radiator from said head and an offset adapted to be removably attached to the back of said head and arranged when so attached to support said head upon a wall at a predetermined distance therefrom.
7. A radiator hanger comprising a head formed with the back adapted to be hung upon a wall, means for suspending a radiator from said head, an offset adapted to be removably attached to the back of said head and forwardly projecting flanges on said offset adapted to engage said head and maintain the same at a predetermined distance from a supporting wall.
8. The combination with a substantially horizontal anchor bolt of a sheet metal head adapted to support a radiator, a back panel on said head having a forwardly projecting flange disposed to bear against the coils of a radiator, said back panel being formed with substantially vertical slots restricted toward the upper ends, and an off-set provided with lugs formed to be inserted in said slots to engage said head, said off-set being adapted to be supported on said bolt to maintain 50 said head in spaced relation with the wall.
9. A radiator support comprising in combination supporting means, a horizontally projecting member carried by said supporting means, means for supporting a radiator wholly from said horizontally projecting member, a second member carried by said first mentioned supporting means and provided with a plurality of openings adapted to receive a bolt, a bolt for securing a radiator to said second member adapted to be inserted between sections of the radiator and engaging means on an end of said bolt adapted to be selectively engaged with said second member adjacent to any of said openings which is nearest alignment with the space between radiator sections, said openings being formed to receive said bolt with said engaging means thereon.
10. A sheet metal wall bracket for the purpose set forth, having a vertically disposed wall-engaging portion, a horizontally disposed radiator hanger supporting portion longitudinally slotted for receiving and permitting adjustment of a hanger supporting element, and an outer vertical portion substantially parallel with the wall-engaging portion and slot, bent inwardly at its upper end and having a row of longitudinally arranged vertically disposed upwardly opening slots therein, extending to a point below the bend line.
11. A sheet metal device for the purpose set forth, having an inner vertically disposed attaching portion, a horizontally disposed hanger engaging portion, longitudinally slotted, an outer vertical flange portion bent inwardly at its upper edge and having a series of vertically disposed upwardly opening tie-rod-receiving slots, extending below the bend line.

In testimony whereof, we have hereunto signed our names to this specification.
